UNITED STATES PATENT OFFICE

HENRY CAVE, OF HARTFORD, CONNECTICUT, ASSIGNOR TO THE FULLER BRUSH COMPANY, OF HARTFORD, CONNECTICUT, A CORPORATION OF CONNECTICUT

MOP MAKING MACHINE

Application filed June 13, 1930. Serial No. 460,889.

This invention relates to that class of machines employed for making implements more particularly employed for cleaning purposes, and an object of my invention, 5 among others, is the production of a machine for making mops or similar articles that shall embody simplicity in construction and operation and that shall be particularly efficient as to the results produced thereby.

10 One form of a machine embodying my invention and in the construction and use of which the objects herein set out, as well as others, may be attained, is illustrated in the accompanying drawings, in which—

15 Figure 1 is a top view of a machine embodying my invention with some parts removed and other parts broken away for clearness of illustration.

Figure 2 is a view in front elevation.

20 Figure 3 is a view approximately on the dotted line 3—3 of Figure 2.

Figure 4 is a similar view on a plane denoted by the dotted line 4—4 of Figure 2.

25 Figure 5 is a view in section on a plane denoted by the dotted line 5—5 of Figure 4, the scale being enlarged.

Figure 6 is a view similar to Figure 5 but illustrating the position of parts of the machine in readiness to insert a core wire and 30 the mop material in a trough shaped back.

In the accompanying drawings the numeral 10 denotes the bed or table of my improved machine that may be supported by legs 11, preferably of angular shape and 35 which table and legs may be composed of any suitable material. A motor 12 may be secured to one of the legs as a means for furnishing power to drive the machine, or other suitable driving mechanism may be employed. The power may be applied to a driving shaft 13 as by means of a belt or other suitable connection, said driving shaft being mounted in bearings 14 secured to the back edge of the bed or table 10.

40 This machine contemplates the manual introduction thereto of parts and material to constitute the mops or other cleaning implements, and the machine is also so arranged that it is readily adaptable for manual operation to a greater or lesser extent. As here-

in shown the mechanism is operated manually to force a rod resting upon mop material in the form of numerous threads into a back of trough shape, said material being folded or "doubled" as it is forced into the back. 55 The sides of said back are then closed together to secure the rod and mop material firmly within said back.

This mechanism comprises two plate levers 15 having their front edges formed as main 60 jaws, said levers being hinged at their back edges to opposite sides of an opening extending across the table, said levers being of corresponding shape each to the other, and of a length at least equal to that of a mop to be 65 formed in the machine. In the structure herein shown the levers are supported by blocks 16 secured in any suitable manner to form opposite edges of said opening in the table, a pintle or pivot 17 attaching each lever to a block.

70 End closing jaws 18 are pivotally supported in notches in the edges of the levers 15 near opposite ends thereof, there being a pair of end closing jaws near each end of each 75 pair of levers 15, the jaws of the latter being shaped to cooperate with the jaws 18 to close the edges at the ends of the back together, while the main jaws between the jaws 18 are shaped to leave a space between the edges of 80 the back sufficient to contain mop material.

These plate levers or jaws are so arranged as to be readily adapted for manual or mechanical operation, the latter being shown herein wherein the levers 15 are operated by 85 links 19 pivotally attached to each lever, preferably at opposite sides of the lengthwise center thereof, each link having a guide stud sliding in a guideway 20 in one of the sides 90 of an inverted U-shaped bracket secured to the under side of the bed 10. A roller 95 mounted on each link engages in a cam groove in a cam 22 secured to a cam shaft 23 mounted in bearings secured to the edges of the bed or table 10.

The end closing jaws 18 have, at their ends opposite the back closing ends thereof, rollers in contact with cams 24 sloping in opposite directions on opposite sides of the top of a cam block 25 supported on ledges on the sides 100

or plates 21 of the U-shaped bracket hereinbefore mentioned, said cams operating, as the jaws 18 are carried down by the downward and closing movement of the levers 15, to separate the roller bearing ends, thereby swinging the opposite ends or jaws proper toward the main jaws, and cooperating with the main jaws to close the ends of the trough shaped back 26 together.

These trough shaped backs are manually pushed into the grooves between the edges of the main jaws, as shown in Figure 6, and rods 27 comprising the cores of the mops are in a similar manner pushed into a trough extending lengthwise through a rod carrier comprising a head 28 attached at opposite ends to the lower ends of plungers 29 slidably mounted in brackets 30 secured to and rising from the bed or table 10 near opposite sides thereof. A rod holding blade 31 is pivotally supported by the head 28 and has a lip at its lower edge on which the rods 27 rest, as shown in Figures 5 and 6 of the drawings. A plunger blade 32 is supported at the lower end of guide rods 33 slidably mounted in the brackets 30, both of said rods having toothed racks meshing with the teeth of plunger actuating gears 34 secured to an actuating shaft 35 manually actuated as by a handle 9. The plungers 29 are connected with and for operation by the guide rods 33 by plates 36, springs 37 being interposed between said plates and shoulders on the rods to provide a yielding connection between the parts. The blade 32 extends through slots 38 at opposite ends of the head 28.

It will now be seen that operation of the handle 9 will cause the rods 33 and the blade 32 to be forced downwardly, thereby forcing a rod 27 out from the pocket between the head 28 and the rod holding blade 31. Said rod is forced by the blade 32 against the top surface of the mass of mop material 39 extending across the mouth of the groove in the mop back 26. Movement of the plunger blades continuing the rod and mop mass are forced into the groove in the mop back, the rod holding blade 31 having been forced away from the blade 32 to permit the rod 27 to pass out of the pocket. When the rods 33 are forced down they move some distance independently of the plungers 29 and head 28 while tensioning of the springs 37 takes place to eventually move the head 28 downwardly against the tension of retracting springs 40 exerting a force upwardly on said head. The head 28 is thus moved against the thread mass, clamping said mass between the head and one of the jaws 18 to hold the mass from backward movement at this point. The springs 37 are under sufficient tension at this time to hold the head 28 in its lowermost position while the blade 32 moves upwardly independently of the head. When the springs 37 are sufficiently

untensioned the head and blade move upwardly together until they finally assume the position shown in Figure 5.

A feeding mechanism actuating cam 41 receives in a cam groove therein a roller on a stud projecting from a feed actuating lever 42 pivotally mounted in a supporting bar projecting from the under side of the bed or table 10, and as shown in Figures 1, 2, and 4 of the drawings. A feed actuating bar 43 is connected at one end to the lever 42 by a pivot adjustable lengthwise of the lever to secure a greater or lesser amount of movement of said bar in the swinging movements of the lever. At its opposite end said bar is slidably mounted in a rest 44 depending from a bracket 45 secured to and projecting from the under side of the bed or table. A rack 46 is carried by the bar at this end thereof, the teeth of said rack meshing with the teeth of a gear 47 secured to a shaft 48 rotatably mounted in the bracket 45 and having a gear 49 secured thereto and meshing with a pinion 50 secured to a shaft 51 rotatably mounted in the bracket 45. The shaft 51 has gears 52 secured thereto at or near opposite ends, said gears meshing with the teeth of feed racks 53 mounted for sliding movement at opposite edges of the bed or table and between gibs 54 secured to the table, and as shown in Figures 1, 2, and 3 of the drawings.

After each operation of the machine a completed back 55 with the mop material secured thereto is formed, but at first they are all contained in a continuous length of the mop material. The ends of the back project outwardly beyond opposite edges of the mop strip, as shown in Figures 1 and 3 of the drawings. This strip with the several mop backs having the projecting ends is extended along the bed for some distance until said strip is subjected to the action of a cutter that severs the strip into separate mop structures, each comprising a back with the mop material projecting substantially to the same extent on opposite sides of the back.

In the machine shown herein the actual feeding operation takes place near the cutting device and at such distance from the initial forming mechanism hereinbefore described for securing the mop material in the backs that several backs are located between the initial forming mechanism and the feeding members. Therefore, during the first few operations of the machine the strip 39 of mop material is moved by hand until the first back of the strip is in position for its projecting end to be engaged by a pair of feeding latches 56, each member of said pair being located opposite the other member and being secured to a plate 57 attached as by means of screws to one of the racks 53. A guide strip 58 of angular shape in cross-section to receive and guide the projecting ends of the backs 55 is supported on the gibs 54 as by means of blocks

59 that are secured to said gibs, said strips overlying said ends.

As the racks are reciprocated in unison with the operations of the mechanism for securing the mop material to the backs the latches 56 are moved under the projecting ends of the mop back, said latches yielding or moving downwardly against the force of springs and passing underneath said ends. After passing said ends the latches rise under the influence of their springs in position to engage said projecting ends on movement of the racks in the opposite direction and thereby move the strip forward a one-step distance.

15 It is not essential to my invention that any particular type of feeding mechanism be employed, or, in fact, that any be used, but that above described has been found to produce satisfactory results.

20 Pairs of holding latches 60 are secured at convenient points to rails 61 extending on opposite sides of the mop strip and along which rails the projecting ends of the mop backs are moved, one of these latches being 25 located at the opposite end of a mop strip from another of said latches. They are preferably spring pressed upwardly and yield downwardly against the force of their springs when engaged by the projecting ends of the 30 mop backs as the strip is pulled along. The feeding latches 56 are preferably moved to substantially the same extent on opposite sides of and across a cutter slot 62 formed in the table.

35 A cutter mechanism of any desired construction is located to sever the mop material to complete the formation of each brush structure, this mechanism, except in combination with other parts, forming no part of my present invention. Briefly described, this mechanism comprises a swinging frame having a cutter shaft 63 rotatably mounted thereon and driven as by means of a belt 64 from a pulley secured to the driving shaft 13. A cutter, of circular type, is secured to said shaft in position to be swung upwardly by the frame through the slot 62 in the bed.

40 A hood or shield 65 is pivotally mounted at one side of the table projecting thereacross to cover the slot 62. Said hood is connected with the swinging frame hereinbefore referred to by a flexible connection 66 secured at one end to the hood and at its opposite end to said swinging frame, said flexible connection passing around several sheaves, as shown in full and dotted lines in Figure 2 of the drawings. One of these sheaves 67 is rotatably mounted in a lever 68 secured to a shaft 69 rotatably mounted in a bracket depending 45 from the under side of the table, and as shown in dotted lines in Figure 2. Said shaft has an arm 70 secured thereto and a cutter actuating bar 71 is pivotally attached to the outer end of said arm. The bar 71 has a guide slot 50 through which the shaft 23 passes, that end

of the bar opposite the arm 70 having a roller in engagement with the periphery of a cutter actuating cam 72 for imparting reciprocating movement to the cutter frame and hood in unison with the other operations of the machine. Said bar 71 when moved by the cam 72 exerts a pull upon the connection 66, and as the hood or shield 65 offers less resistance to movement than does the swinging cutter frame, said hood is moved down to 75 cover the slot 62, and when it encounters the table it offers resistance to further movement and consequently the swinging frame bearing the cutter is raised, carrying the edge of the cutter through the slot 62 and through 80 the thread mass, severing the outer ends thereof.

85 In the operation of the machine, it being assumed that the strip of mop material has been extended far enough for engagement of the projecting ends of the mop backs with the feeding latches, and the machine being at rest, the handle secured to the shaft 35 is rotated, thereby first moving the plunger blade 32 downwardly to force a rod 27 out of its pocket in the head 28 and against the strip of mop material. After the blade 32 has been moved a certain distance the tension of the springs 37 will become sufficient to move the head 28 downwardly against the strip of 90 mop material to clamp the latter in place. While the parts are held in this position a clutch operating handle 73 secured to a clutch operating shaft 74 is rotated by the operator to effect operation of a clutch and set the 95 machine in motion. This starts operation of the cam shaft 23 that results in the clamping operation of the strip closing jaws, thereby firmly securing the material in the 100 mop back. The strip of mop material is given 105 a one-step movement and the cutter mechanism operates to sever the end of the strip and produce a mop structure.

110 The clutch mechanism is of that well known type called a one-revolution clutch, that is, the cam shaft 23 has one complete rotation imparted to it at the end of which it ceases to operate. This one complete rotation effects one complete operation of the machine. As the particular structure of this clutch, aside from its being a one-revolution clutch, is immaterial to the present invention, and as it may embody any of the well known types of one-revolution clutches, only a brief 115 description will be given herein.

120 The main shaft 13 extends into a housing 75 within which the clutch is located. A worm on said shaft meshes with a worm wheel 77 forming one member of a chain of gearing terminating in a clutch sleeve 78 within which clutch members of semi-round shape in cross section and of a well known type are located and serve to connect the sleeve 78 with the cam shaft 23.

125 As hereinbefore noted one operation of 130

the machine is effected by one rotation of the cam shaft at the end of which the machine comes to rest, the mop strip having been moved one step in position for operation of 5 the manually actuated device to insert a rod and fold the mop material into a mop back.

I claim—

1. A mop making machine including plate levers pivotally mounted for movement of 10 their edges toward and from each other, said edges being of jaw formation to compress a grooved back strip between them, a reciprocating plunger, a link connecting said plunger with each of said plate levers, means for operating said plunger, means for supporting mop material extended across the open edge of said strip, means for inserting said material into the groove in said strip, and means for application of force to said inserting 15 means to effect said operation.
2. A mop making machine including a table having an opening therein, a pair of plate levers pivotally mounted relatively to said opening for movement of their opposite edges toward and from each other, said edges being of jaw formation to compress a grooved back strip between them, means located underneath said table for operation of said levers, means located above said table for insertion of mop material into the groove in 20 said strip, and means for manual application of force to said inserting means to effect said operation.
3. A mop making machine including plate levers pivotally mounted for movement of 25 their edges toward and from each other, said edges being of jaw formation to compress a grooved back strip between them, means for operating said levers, means for supporting mop material extended across the open edge of said strip to receive a rod thrust upon 30 said material, an inserting member mounted for reciprocating movement above said material and having means to receive and support a rod, and means for operating said inserting member to insert said rod and material into the groove in said strip.
4. A mop making machine including plate levers pivotally mounted for movement of 35 their edges toward and from each other, said edges being of jaw formation to compress a grooved back strip between them, means for operating said levers, means for supporting mop material extended across the open edge 40 of said strip, an inserting member mounted for reciprocating movement above said material and having a rod receiving pocket into which a rod may be pushed from the end thereof, and means for operating said inserting member to insert said material and rod into the groove in said strip.
5. A mop making machine including plate levers pivotally mounted for movement of 45 their edges toward and from each other, said edges being of jaw formation to com-

press a grooved back strip between them, means for operating said levers, means for supporting mop material extended across the open edge of said strip, an inserting member mounted for reciprocating movement above 50 said material, means on said inserting member to receive and hold a rod, a plate comprised in said inserting member having its edge formed to engage said rod, and means for operating said inserting member and said plate to insert said material and rod into the groove in said strip.

6. A mop making machine including plate levers pivotally mounted for movement of 55 their edges toward and from each other, said edges being of jaw formation to compress a grooved back strip between them, means for operating said levers, means for supporting mop material extended across the open edge of said strip, an inserting member including 60 two supports to receive a rod between them, said supports being relatively movable to release said rod, said inserting member also including an inserting blade having its edge formed to engage a rod, and means for operating said inserting member and blade to insert said material and rod into the groove in said strip.

7. A mop making machine including plate levers pivotally mounted for movement of 65 their edges toward and from each other, said edges being of jaw formation to compress a grooved back strip between them, means for operating said levers, means for supporting mop material extended across the open edge of said strip, an inserting member including 70 means to receive and support a rod and a blade having its edge formed to engage said rod, and means for application of force to said inserting member including said blade to force said rod against said material and said material and rod into the groove in said strip.

HENRY CAVE.
